(57) **CLAIM**

The ornamental design for a pool/spa remote control unit, as shown and described.

DESCRIPTION

FIG. 1 is a perspective view showing the front and right sides of a pool/spa remote control unit embodying the new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side elevation being a mirror image of the right side.
